UNITED STATES PATENT OFFICE

WILLIAM J. DEMMING, DECEASED, LATE OF LAKEWOOD, OHIO, BY AGNES M. DEMMING, ADMINISTRATRIX, OF LAKEWOOD, OHIO, ASSIGNOR TO MULTIGRAPH COMPANY, OF WILMINGTON, DELAWARE, A CORPORATION OF DELAWARE

CASTING MACHINE

Application filed December 18, 1930. Serial No. 503,163.

This invention relates to casting machines, and especially automatic machines for casting small articles at a high rate of speed, and automatically delivering them to a suitable receiving receptacle. The machine is adapted for casting articles of various shapes, either of molten metal or of some composition, as for instance, a phenol compound such as bakelite. It has however been designed with special reference to casting printers type.

This invention has a rotary mold carrier, a melting pot from which molten metal may be ejected into the molds as presented, and means for receiving discharge from the mold carrier. Type casting machines having this broad characteristic have been proposed in the past, but such machines have usually been intermittent in their movements. This materially reduces the speed of operation of a continuously rotary machine, first, because of the lull between periods of movement of the rotor; and, second, because a mold carrier of a casting machine is usually of considerable weight and, if it is rotated at any great speed the momentum precludes instantaneous stopping of the parts, and causes quite a delay in the movement of the mechanism. The latter is especially true where the mold carrier embodies a comparatively large number of individual molds or dies.

The above mentioned delays would not be apparent in a machine where the mold carrier rotates continuously but when continuous rotation is considered, one of the primary difficulties that has heretofore been encountered, and has heretofore prevented practical use of a continuously rotated casting machine is the problem of discharging the castings. This is especially true in the case of such forms of castings as printers type, wherein a great deal of time would be lost if it were necessary to assort delivered type, and moreover wherein it is highly desirable to retain the face of the type not only in the same plane, but in that plane without the type being turned, so that the character thereon may always be in proper position for use. It is also frequently desirable in a machine for this purpose that a plurality of matrices, each differing from the other, be provided,

so that an entire font or other assortment of type may be cast without necessitating frequent changing of the matrices. The casting machine, in which has been embodied this invention, is so constructed that a plurality of matrices, having different characters thereon, may be used, and that the type at the point of ejection will always lie with its face in a predetermined position.

When the casting machine is of the character above specified, it is particularly desirable to provide a receiving means into which the casts may be discharged, and which will retain them in their relative positions, moreover, which will be of such a nature as will not interfere with the continuous rotation of the mold carrier.

Heretofore this has been attempted by the use of conveyors which carried the type away one at a time, but in such cases great difficulties were encountered in assembling the type or castings from the conveyor into groups, each group containing castings or type having the same character thereon, and each type bearing the same relationship to the other.

This invention contemplates the provision of a simple mechanism which may operate in synchronism with the molding or casting mechanism, and which will be adapted to receive the type from the molds, retaining them in their relative positions and grouping the type so that a quantity of each character, i. e., a quantity of type from each mold is collected together as a unit.

The general object of this invention is to provide a casting machine, capable of high production and wherein the castings may be discharged in stacked relationship and in which the difficulties heretofore mentioned are overcome. A further object is to provide a rotary carrier which has a number of type receiving members corresponding to the number of molds in the mold wheel, whereby each type mold will discharge its product into its respective receiving channel.

Another difficulty encountered in such a mechanism, is the fact that a mold carried by a rotary carrier and a receiving unit carried by a receiving member are actuated only in juxtaposition instantaneously. Some slight

clearance in the type receiving channels may permit the mold to be positioned over the channel for a slight annular distance. This distance is necessarily extremely slight, where the mold wheel is rotating at any appreciable speed, because the interval of time in which the type must be ejected from one rotating member to the other is comparatively small.

Hence, another object of this invention is the provision of means whereby the type may enter a guideway which is adapted to lie between the type casting mechanism and the type receiving mechanism, which guideway is capable of movement relative to both mechanisms and by means of which the type may be discharged from the casting mechanism, at various points other than the exact point of juxtaposition.

Due to the difficulties heretofore mentioned, rotary type casting machines, especially those where the rotation is continuous, have rarely been used, hence the development in such casting machines has heretofore been neglected. However, when the difficulties of discharging the castings are overcome, a result accomplished by this invention, it was found desirable to improve the casting machine itself so that it will be comparatively simple and capable of being operated at a comparatively high rate of speed.

Accordingly, one of the objects of this invention is the improvement of the casting mechanism itself, enabling it to operate at a high rate of speed, this improvement relating to the rotary carrier having a plurality of molds which operate automatically as they assume various positions for making the casting and shearing the sprue, and for effecting discharge. All of these features will become apparent from the detailed description of a preferred embodiment hereinafter given.

Fig. 1 is a plan view of one form of a casting machine, embodying the invention, being a form which is especially adapted for use in the casting of printers slugs, or type; Fig. 1A is a fragmentary plan of a portion of the casting machine shown in Fig. 1 and extending to the left thereof; Fig. 2 is a transverse vertical section of the casting machine, illustrated in Fig. 1, and indicated by the line 2-2 on Fig. 1; Fig. 3 is a section, in the same plane as that of Fig. 2, illustrating some of the parts, and on a larger scale; Fig. 4 is a sectional detail of a mold and a portion of metal feeding nozzle; Fig. 5 is a horizontal section taken through portions of the mold carrier and melting pot, and is indicated by the line 5-5 on Fig. 3; Fig. 6 is a horizontal section on an enlarged scale through a mold, and is taken in the same plane as Fig. 5; Figs. 7, 8 and 9 are horizontal sections, taken in different planes, through the mold members, as indicated by the lines 7-7, 8-8 and 9-9 on Fig. 3; Fig. 10 is a vertical section through the mold, illustrating the manner of lubricat-

ing the mold members, and is indicated by the line 10-10 on Fig. 8; Fig. 11 is a horizontal section, through certain of the mold supporting members, and is indicated by the line 11-11 on Fig. 3; Fig. 12 is a sectional detail of another mold supporting member, and is indicated by the line 12-12 in Fig. 5; Fig. 13 is a vertical section through the mold carrier and a mold, indicated by the line 13-13 on Fig. 5 and illustrates a mold in the sprue shearing position; Fig. 14 is a vertical section through the die carrier and a die at the point of casting discharge, and is indicated by the line 14-14 in Fig. 5; Figs. 15, 16 and 17 are perspective views showing a type and sprue, and is illustrative of one of the forms of castings which the machine is capable of producing; Fig. 18 is a longitudinal vertical section, taken through the melting pot and a portion of the operating mechanism therefor, and is indicated by the line 18-18 in Fig. 2; Figs. 19 and 20 are detail sections of the melting pot pressure regulator, and are indicated by the lines 19-19 and 20-20 on Fig. 2; Fig. 21 is an enlarged vertical section through a portion of the melting pot and pump mechanism, and is indicated by the line 21-21 on Fig. 1; Fig. 22 is a vertical section in a plane at approximately a right angle to the plane of Fig. 2, illustrating the casting discharge and the receiving mechanism, and is indicated by the line 22-22 in Fig. 1; Fig. 23 is a detail section taken along the same plane as Figs. 14 and 22 and being approximately that portion of Figs. 14 and 22 which is enclosed by the dot and dash circle 23 on those figures; Figs. 24 and 25 are horizontal sections of the casting receiving mechanism, taken along the lines 24-24 and 25-25 of Fig. 23; Figs. 26 and 27 are perspective views illustrating guiding members for guiding the castings as they are discharged from the casting mechanism; Fig. 28 is a diagrammatic illustration of the operation of the type-guiding mechanism during discharge; Fig. 29 is a horizontal section illustrating the driving mechanism for the casting discharge drums, and is indicated by the lines 29-29 on Fig. 22; Fig. 30 is a horizontal section through a portion of the casting receiving mechanism, and is indicated by the line 30-30 on Fig. 22; Fig. 31 is a fragmentary plan illustrative of a method of adjusting the driving mechanism for the casting receiving units; Fig. 32 is a vertical section through a portion of the adjusting mechanism for aligning the receiving drums with the type casting mechanism, and is indicated by the line 32-32 on Fig. 30.

In the embodiment shown, there is provided a main frame member 10, adapted to support the different units of the casting machine, namely, the die carrier, the melting pot, and the casting receiving mechanism. The frame 10 comprises a base 11, having

upstanding sides 12, which support a head, or top portion 14.

Located vertically within the frame 10 is a main drive shaft 15, journalled in bearings 16 and 17, associated with the top and base frame members 14 and 11 respectively. The bearing 16 is retained in position on the shaft 15 between a collar portion 18 of the shaft and a clamping nut 19, and is retained 10 in a recess in the frame member 14 by a plate 20, thereby supporting the shaft against vertical displacement at a point adjacent the top frame member 14. The lower bearing 17 is secured to the shaft between the hub 15 21 of a gear member 22 and a clamping nut 23.

Due to the heat applied to the casting mechanisms, it is desirous to permit vertical expansion of the shaft 15. The bearing 17, therefore, is mounted, free, for vertical movement 20 in a bearing box 24 secured to the base 11 by suitable bolts, not shown. The shaft 15 may be driven in any suitable manner, such as by a motor 25 and gearing hereinafter to be described.

25 A mold carrier 40 is mounted on a tapered portion 30 of the shaft 15, which extends above the frame member 14 and the bearing 16. The mold or die carrier 40 is drivingly secured to the tapered portion 30 by means 30 of a key 31 and a clamping nut 32. The mold carrier 40 is drum shaped and comprises a hub 41, a horizontal web 42, and a rim 43. There is sufficient clearance between the web portion of the mold carrier and the top frame member 14 to provide for the operation of suitable mold members hereinafter to be described. The web or base portion of the die carrier has a number of equally spaced radial grooves 45, and the rim portion 43 is 35 provided with a corresponding number of vertically extending grooves 46, which are wider than the grooves 45 but are centrally located with reference to them. Associated with each pair of grooves 45 and 46 is a die 40 or mold comprising relatively stationary members and relatively movable members.

45 Each die or mold comprises a matrix carrier 50, which is mounted for reciprocation in the corresponding groove 45. Associated with each matrix carrier is a matrix 51 which lies in a recess 52 of the matrix carrier. Each matrix has a character die portion 53, which, when in casting position, is substantially a continuation of the inner face 47 of the groove 46. The characters may be identical with each other or may differ from each other, and the molds likewise may be adapted to cast type of the same or different shapes and sizes.

The matrix carrier is retained in the groove 55 45 by means of suitable locking plates 55, best illustrated in Figs. 3, 5 and 12. Where the molds, contained in the mold carrier, are of an even number, each locking plate 55 retains two matrix carriers in position. 60 However, in the embodiment illustrated, there

is shown a mold carrier wherein there is an odd number of molds, and in this case, one locking plate, indicated at 55a, is used to support the odd matrix carrier. The locking plate 55 in the embodiment illustrated, 70 is a flat washer-like member and is threaded to a stud 57, which passes through an opening in the mold carrier 40. A small spacing washer 58, threaded to the stud 57, adjacent the plate 55, acts as a jamb-nut to prevent relative rotation between the plate 55 and the stud, as well as to space the plate 55 in the proper position below the mold carrier, relative to the under surface of the matrix carrier 50. The stud 57 has an enlarged 75 flanged portion 58 as its upper end, which bears against the web 42 of the mold carrier, thereby retaining the plate 55 in position relative to the die carrier. The stud 57 is also provided with a squared head portion 59, by means of which the locking plate 55 may be rotated, so that a flattened portion 60 of the plate may be presented to the matrix carrier, in which case the carrier will be free of the plate 55 and may readily be removed. 80

To retain the plate 55 in a locked or engaged position, in which position the plate 55 underlies the matrix carriers, there is provided a spring-pressed plunger 61, suitably mounted in the mold carrier and adapted to engage an opening 62 in the plate 55. When it is desired to remove one of the matrix carriers, the plunger 61 is withdrawn, the stud 59 is rotated, towards the carrier to be removed, until an abutment 62 of the spacing 90 washer 58 engages a suitable stop in the form of a pin 63, mounted in the upper face of the mold carrier, at which time the flattened side 60 of the plate 55 will be in position to permit the matrix carrier to be removed by a downward movement. 100

In the embodiment shown, the molds are designed for casting printers type, particularly such forms as are used on the standard multigraph. This form is best illustrated in 110 Figs. 15 and 17 and comprises a head 70, carrying a suitable printing character 71, and joined by means of a web 72 to a suitable base 73. It is found convenient to cast such type with the web in a position parallel to the direction of movement of the casting ejecting mechanism; in the embodiment illustrated, this is vertical. 115

It will be noted that each of the two opposing parallel sides 74 of the type illustrated in Fig. 17 lie entirely in one plane, while the two sides 75 each lie in substantially three different parallel planes. Therefore, it is convenient to make those sides of the mold, 120 which are to form the sides 75 of a plurality of pairs of members 77 (see particularly Fig. 6). Each pair of opposing members 77 is adapted to mold a portion of the type, namely, one pair of members for the head, one for the web and one for the foot. 125 130

The matrix carrier 50 has an extending portion 65, which underlies the slot 46 of the die carrier. This portion 65 serves as the bottom for the mold cavity, while the matrix 51 serves as one side.

In order to obtain a more perfect casting and to insure that the castings will be of the same relative height, a sprue mold 79 is provided adjacent the type mold 90, the sides of which are embraced by plates 81. Suitable bolts 83, passing through openings in a mold retaining plate 82 and the mold members 77 and 81 retain them in position in the slots 46 of the mold carrier 40.

The upper surface of the mold cavity is formed by the lower ends of two vertical bars 85 and 86, which are mounted for vertical movement in extending portions of the mold members 77 and 81 and the carrier 40. The mold member 85 has the same cross sectional shape as the type, while the mold member 86 has the same cross sectional shape as the sprue 78, as shown particularly in Fig. 7. This permits them to be readily reciprocated between the extensions of the mold members 77 and the mold members 81 respectively, and prevents the escape of molten metal. The members 77 and 81 extend downward to contact with the upper face of an extending portion 65 (Figs. 4 and 10) of the matrix carrier, and they extend upward approximately half the height of the rim 43 of the mold carrier. Above the members 77 and 81 are blocks 87 which are secured in position on the die carrier by means of the retaining plate 82 and suitable bolts 88, and act as guides for the bars 90 and 91 which operate the bars 85, 86.

It will be noted that the opening formed between the blocks 87 is substantially rectangular in shape (Fig. 8), and that these blocks are separated by a distance equal to the maximum width of the mold cavity, thus permitting the reciprocation of the members 85 and 86 between them. This permits the bars 90 and 91 (constituting in effect the upper portions of the die members 85 and 86) to be substantially rectangular in shape, whereby the surface friction between them and the associated guideways is materially lessened and the members, themselves, are considerably strengthened. The sections 85 and 90 are interlocked by complimentary hook-shaped portions 92, by means of which they may be raised and lower as a unit, and the members 86 and 91 are correspondingly connected by similar complimentary hooks 93.

It will be seen from the foregoing description that the top face of the mold cavity is formed by the movable mold members 85 and 86; the bottom face of the cavity is formed by an extension 65 of the matrix carrier 50; the innermost side of the mold cavity (that which forms the face of the type) is formed by the matrix members 51; the adjacent sides

are formed by the relatively stationary members 77 and 81. The side of the mold opposite the face is open so that it may coact with a suitable nozzle 100 of the melting pot. However, as the mold is rotated past the nozzle, which is stationary relative to the rotor, a suitable closure plate 101, mounted on the nozzle 100, serves to close the open face of the mold until the casting is sufficiently chilled to prevent distortion.

To conveniently lubricate the vertically movable mold members and their operating bars, oil openings 96 are provided in a plate 97 (see Fig. 10) secured to the tops of the blocks 87. On the side of these openings, which is at the rear, considering their reference with the direction of travel, is an upstanding lip 98 which is adapted to coact with an oil wick 99 suitably carried by some stationary part of the machine and leading downward from an oil receptacle to a position slightly below the tops of the lips 98. Thus, once each rotation of the mold carrier, each mold receives a slight access of oil, which maintains the vertically moving parts in a lubricated condition.

Figs. 2, 3, 4, 5 and 6 illustrate the relative position of the mold parts at the point of casting. In this position the matrix carrier 50, which forms the lower face of the mold cavity extends outward and contacts with the plate 101 of the melting pot, and the movable mold members 85 and 86 are in their uppermost positions. As the mold carrier rotates (in a counterclockwise direction for one looking down on it, see Figs. 5 and 6) the sprue opening 79 of the mold approaches an opening 102 in the plate 101 and the molten metal is then forced from the nozzle 100, through the opening, into the mold cavity, by means hereinafter to be described.

The upper ends of the members 90 and 91 are provided with suitable rollers 94, which are engaged by cams hereinafter to be described, to raise and lower them for the different mold conditions, namely; casting, sprue-shearing and ejecting. The matrix carrier 50 is likewise provided with a roller 95, which will be acted on by cams hereinafter described, so that it will properly move horizontally to cooperate with the members 85 and 86 in the different mold positions.

As the mold carrier continues in its rotation, a stationary annular cam 103, rigidly mounted on the member 14, acting in the roller 95, draws the matrix carrier 50 inwardly, until it reaches a point (illustrated in Fig. 13) where the outer face 61 of the matrix carrier is in alignment with the inner face of the mold member 86, at which time a stationary annularly grooved cam 105, coacts with the roller 94 of the mold member 86 and forces the latter downwardly to the position illustrated in Fig. 13. This causes the sprue 78 to be sheared from the type portion

70 of the casting. As the rotor continues in its rotation, the cam 103 draws the matrix carrier and its matrix inwardly to a point where the face 65 of the matrix carrier clears 5 the mold cavity.

In the latter part of the travel of any matrix carrier while it is in the withdrawn position, the mold member 86 is forced downwardly by means of a stationary annular grooved 10 cam 106 to the position shown in Fig. 23, thereby forcibly discharging the type from the mold cavity. This operation will be referred to later in connection with the description of the type receiving receptacle. The 15 cams 103 and 106 are secured to a bracket 107 attached to a boss 108 on the frame members 14 by means of suitable bolts 109.

It is desirable to cool the mold before the type is ejected therefrom. To this end there 20 is provided a hollow shoe 110, which lies radially opposite the casting point and coacts with the outer face of the molds and mold carrier. The shoe 110 is arcuate shaped and is adapted to coact with a comparatively large 25 portion of the circumference of the mold wheel. The shoe has a horizontal partition 111 dividing it into a passageway 112 through which a suitable cooling liquid may circulate. A pipe 114 leads from a pump or a suitable 30 pressure supply to the shoe, and a pipe 116 leads from the shoe to a drain, thereby providing a circulation of the liquid through the shoe 110 for cooling the mold. This prevents the molds and mold carrier from reaching an 35 excessive temperature, due to the constant application of heat at the casting point.

As the mold wheel continues in its revolution from the discharge position hereinafter described, the cams 105 and 106 return the 40 mold members 85 and 86 to their casting position, while, at the same time, a cam member 116 coacts with the roller 95 of the matrix carrier and returns the latter to its casting position. To prevent undue strain upon the 45 mold members and seepage or leakage of metal, it is desirable that one of the mold members be retained in casting position resiliently. To this end, it is preferable to mount the matrix carrier resiliently.

50 As shown, the cam 116 is pivotally mounted on the cam 103 at 117, and is urged against the rollers 95 of the matrix carriers by means of a spring pressed plunger 118, mounted in a boss 119 on the cam member 103. This provides a resilient mounting in a horizontal plane.

Means is also provided whereby the matrix carrier is resiliently retained in a vertical plane. Mounted in a housing 120 secured to 60 the frame member 12 and in line with the nozzle of the melting pot, is a vertical plunger 121, which carries a roller 122 adapted to coact with the under surface of the matrix carrier, at a point directly below the type casting portion of the mold, when the latter is in

casting position. The plunger 121 is urged upwardly, against the matrix carrier, by a spring 123 retained in the housing 120 by means of a threaded plug 124. The upward movement of the plunger 121 is limited by means of an extended threaded portion 125 of the plunger, which passes downwardly through an opening in the plug 124 and carries nuts 126 adapted to coact with the plug 124.

70 It is likewise desirable to provide a resilient mounting for the matrix carrier when the latter is in the sprue shearing position. As shown in Fig. 13, a plunger 130 having a roller 131 adapted to coact with the matrix carrier, lies directly beneath the type portion of the mold cavity at a point where the sprue portion 78 is severed from the type. The plunger 130 is mounted in a housing 131 secured to the frame member 12 and has a threaded portion 132 extending through the bottom 133 of the housing 131 and is held against undue vertical movement, by means of the nuts 134. A suitable spring 135 urges the plunger upward.

75 As only the upper portion of the shield plate 101, which is associated with the nozzle of the melting pot and closes the mold cavity, bears against the mold carrier 40, it is desirable to provide means to adjustably support the lower portion of the plate, so that it will bear evenly against the mold wheel, thereby preventing the seepage of molten metal between the plate and the mold carrier. It is preferable that such means be adjustable, because while, the mold wheel is constantly rotating and to some extent being cooled, the lower portion of the shield plate 101 is supported by a relatively stationary member 136, wherefore some differences in expansion and 80 wear will exist.

85 The adjustment above mentioned is best 90 illustrated in Figs. 1, 3 and 11. As there shown, the member 136 is mounted for sliding movement in a block 137, mounted on the frame member 14. The member 136 is provided with an opening 138 slightly larger in cross section than the combined section of the plunger 121 and the roller 122, so that there 95 will be sufficient clearance to permit the member 136 to be moved without disturbing the roller 122. The inner side of the member 136 is tapered as at 140 and coacts with a wedge 141, which is slidably mounted in the block 137 for movement at approximately 100 right angles to the movement of the member 136. The wedge 141 is adjusted by means of 105 suitable screws 142 threaded in the block 137 and coacting with opposite ends of the wedge, to move it in one direction or the other, as is required, to project or allow the retraction 110 of the member 136. The screws 142 are supplied with suitable lock nuts 144, so that they 115 may be locked securely in position, as this 120 adjustment between the member 136 and the 125 130

plate 101 need be made only at infrequent intervals.

The melting pot and pump may be of any well known construction. However, as the 5 mold carrier, heretofore described, is adapted for continuous rotation at a relatively high speed, it is preferable to use a melting pot and pump, which will maintain the molten metal at a constant predetermined pressure, 10 and which will supply metal of such constant pressure under a practically continuous flow.

As illustrated in Figs. 1, 2 and 18 to 21, a 15 mechanism has been provided which, generally speaking, comprises a pump 151 mounted in a suitable reservoir or melting pot 150, which is provided with a pressure regulator 152 and a nozzle 153 and is heated by means of a burner 154. The melting pot is substantially circular in cross section and has on opposite sides thereof outwardly extending horizontal ribs 155, which rest on bracket members 156 integral with the main frame casting 10. If desired, to facilitate movement of 20 the melting pot towards the mold carrier, suitable rollers (not shown) may be interposed between the flanges 155 and the brackets 156.

The melting pot is yieldingly retained in 25 contact with the mold carrier by means of a link 158 (Fig. 1A) pivoted to a lug 159 of the melting pot, diametrically opposite the nozzle 153. The other end of the link is pivoted to a plunger 160 slidably mounted in a 30 yoke 161 secured to the brackets 156. A spring 162 mounted on the yoke 161, urges the plunger 160, the link 158, and the melting pot towards the mold carrier. It is desirable at times when the machine is idle to withdraw 35 the melting pot from contact with the mold carrier. Therefore, one arm of the yoke 161 is pivoted to one of the bracket members 156, as at 165, while the other arm of the yoke is secured to the other bracket 156 by 40 means of a suitable bolt or wing-nut 163.

The metal pump is best illustrated in Figs. 1, 2, 3, 4, 18, 19 and 21, and comprises a plurality of pistons 170, mounted for reciprocation in cylinders 171 in a boss 172 of the melting pot. The cylinders are lined with sleeves 173, pressed in openings 174 in the boss 172, as illustrated in Fig. 21. The boss 172 and each sleeve 173 is provided with an inlet port 175, to permit molten metal to flow from the 55 pot into each pump cylinder, and on the downward movement of a pump piston 170 the metal is forced downwardly through an opening 176 in the cylinder, forcing a check valve 177 downwardly against a boss 178 of a plug 179, at the base of the melting pot. Each check valve 177 has a slot 180 by means of which metal passes from the cylinder to a passageway 181 in the boss 172.

As the plunger 170 is drawn upwardly, the 60 check valve 177 is forced upwardly due to the

pressure in the passageway 181 and the opening 180 in the check valve is closed by contact with the sleeve 173, thereby creating further vacuum within the cylinder. When the piston reaches a point above the inlet port 175 molten metal will again flow into the cylinder and the cycle of operation will begin anew.

The pressure regulator 152 is mounted in the passageway 181 (Fig. 21) between the 70 pump and the nozzle. The molten metal passes from the passageway 181 into a chamber 182, which communicates with the pressure regulator 183. The pressure regulator piston or plunger 183 is mounted in a sleeve 184, which is pressed in an opening 185 in the boss 172.

As illustrated in Fig. 2, the plunger 183 has an upwardly extending portion 186 slidably mounted in a housing 187, which housing is removably mounted in a bracket 188 85 extending from the upper face of the melting pot. A spring 189 bearing at its upper end against a nut threaded into the housing, and at its lower end against a collar 190 rigidly secured to the plunger 186, acts to urge the plunger downward against the molten metal in the cylinder 182. The force on the spring 186 may be readily adjusted by means of the plug 190 which has a slotted face suitable for 90 use with a spanner wrench.

It is highly desirable that the plunger 183 be mounted so that it may readily be withdrawn for purpose of cleaning the passageways if at any time the metal should show a tendency to chill or the conduit become 95 clogged. The housing 187 therefore is slidably mounted in the bracket and is provided with a pair of locking lugs 192 and 193. The lugs 193 are adapted to pass through recesses 194 in the bracket 188. When the lugs align 100 with the under surface of the boss (Fig. 19). The housing 187 will then be rotated through approximately one-quarter turn, the lugs 193 then underlie the boss and the lugs 192 will 105 overlie the brackets locking it in position 110 against relative vertical movement.

The nozzle 154 is mounted in a recess 200 in an external boss 201 of the melting pot. A passageway 202 leads from the pressure regulator to the recess 200. The nozzle 154 has a converging portion 205 having an opening 206 in the vertex thereof 207, and which is adapted to enter an opening 208 in the plate or shield 101 and align with the opening 102, thereby permitting the flow of metal 115 from the pump to the sprue or casting cavity.

Mounted within the nozzle is a plunger 209 having a tapered nose 210, adapted to coact with the inner tapered surface 211 of the nozzle, and serve as a valve. In the position 120 shown in Figs. 3 and 4, the plunger is in a closed position. A rock arm 212, pivotally mounted on the bracket 188 as at 213, coacts 125 with a slot 214 in the plunger 209 to reciprocate the latter. Any means may be used to 130

operate the lever or rock arm 212. As illustrated in Fig. 1, a hand lever 215, is provided which may be integral with the lever 212 and which extends outwardly from the melting 5 pot.

When the plunger 208 has been closed, the pressure due to the continuous action of the pumps will increase until the lower face of the pressure regulator plunger 163 rises above 10 a port 216 in the boss 172. This prevents further increase in pressure, preventing excessive strain on the parts, and maintaining the molten metal at a constant pressure.

To facilitate cleaning of the various passageways of the pumping mechanism, a cleanout plug 217 is provided which is threaded into the boss 172 immediately above the passageway 181. The plug 217 has a passageway 216, which coacts with the passageway 181, and is connected by means of passageways 219 to an annular groove 220 in the underside of an enlarged portion 221 of the plug. This boss, when the plug is in its lowermost position, contacts with the face 25 of the boss 172 preventing the flow of metal from the passageway. The plug may be raised so as to permit the passage of molten metal, thereby providing a circulation to aid in forcing of the metal through the passageways. It will be seen that this cuts down 30 the resistance of the chilled metal to the heated or molten metal by permitting the molten metal to circulate when it reaches an intermediate point, thereby presenting a comparatively hot molten metal to the chilled metal at a point intermediate the pump and the nozzle. The pressure regulator, when removed, serves a similar purpose thereby permitting the chilled liquid in the passageways 35 to be heated with comparative ease.

The pump plungers or pistons are reciprocated by means of suitable connecting rods 222 retained by pins 223a on bushings 223, which are mounted on a crank shaft 224. The shaft 224 is supported directly above the 45 pump cylinder bearings 224a, mounted on the flange or rim of the melting pot. A suitable pulley 225 mounted on the shaft 224 is driven by means of a belt 226 cooperating with a pulley 227, rigidly secured to a shaft 228, which will be hereinafter described.

It will be seen from the foregoing that the melting pot will give a continuous flow of metal at a predetermined pressure, and is well 55 adapted for use with a constantly rotating mold carrier such as used by the casting machine illustrated in the drawings.

The type receiving mechanism is shown in Figs. 1, 14 and 22 to 32. It comprises, in 60 general, a plurality of rotatable drum-like members 250 which carry a series of longitudinal type-receiving guides and are mounted in a rotatable frame 251, so that any one of the drum-like members may be active while 65 the others are idle for the removal of the

type. Two such drums have been shown in the embodiment illustrated.

The frame 251 comprises upper and lower frame plates 252 and 253 respectively, which are joined together by means of upright 70 frame members 254. The upper plate 252 has a stud-like extension 256 on which a bearing 257 is secured, by means of a suitable lock nut 258. The bearing is supported by a bracket 260, which extends from the upper 75 main frame member 14. The bearing assembly above described, is such that the casting receiving frame is supported against vertical displacement, entirely, by means of the bracket 260. The lower plate 253 has a downwardly extending stud-like portion 262 which carries a bearing 263, retained in place against a shoulder 264 by means of a nut 265. The bearing 263 is slidably mounted in a stationary sleeve 266, the construction being 80 similar to that provided for the lower bearing 17 of the main shaft 15, whereby the receiving frame is free for vertical expansion. The member 266 is mounted on an extension 268 of the main frame member 11 by means of 85 suitable bolts, not shown.

While in the embodiment illustrated the receiving frame supports two drums, it may readily be seen that it may support several 90 of such drums. Each of the drums 250 comprises a main shaft 271 mounted by means of bearings 272 and 283 in the rotatable plates 252 and 253 respectively. The bearings 272 are retained in position on the shaft 271 by means of suitable nuts 273 and are supported 95 by the frame member 252.

Now on the lower end of the shaft 271 there is a disc 280 having an upwardly extending hub 281, which is secured to the shaft 271 by means of pins 282. The hub 281 carries the bearing 283 by a nut 277. The bearing 283 is mounted for vertical movement in an opening 276 in the rotatable plate 253. The shaft 271 carries a circular plate 285, which is pinned to the shaft adjacent its upper portion immediately below the plate 252. A similar plate 286 is pinned to the shaft near the lower end thereof immediately above the rotatable plate 253.

In the embodiment illustrated, there are a 115 series of type retaining channels 287 which extend between the two plates 285 and 286 and are equally spaced about their periphery, the channels being formed by means of rail-shaped members, secured to the upper and 120 lower plates, and provided with flanges 289, which overhang the channels 287 and are adapted to enter the grooves between the base and head portions of the type, thereby retaining them against displacement, as illustrated 125 in Figs. 23 and 24.

The receiving channels 287 are located in a predetermined position relative to the mold carrier, in that the uppermost portion of the channel lies in a horizontal plane slightly be- 130

low the bottom plane of the molds, so that when a channel reaches the vertical plane connecting the mold carrier axis and the drum axis, it is disposed immediately beneath the 5 type casting portion of the mold, and the heads 289 of the rails are directly below and adjacent the web portion of the type in the mold.

The mold wheel is constantly rotated, and 10 the drum 270 likewise constantly rotates. Therefore, it is readily seen that the time for discharging the type or castings, from one to the other, is comparatively short. Therefore means is provided for guiding the 15 type from the mold to the carrier, such means being adapted to permit the discharge of the type some distance before the alignment of the mold with its type receiving channel and permitting such discharge to continue 20 some distance after this point has been passed. This is illustrated in Figs. 23 to 28 inclusive, and will now be described.

Each type receiving channel is provided 25 with a guide block 290, which is rigidly mounted in the upper disc 285, immediately above the channel 287. The guide blocks 290 have inwardly extending ribs 291, which serve as continuations of the heads 289 of the rails. The ribs 291 are wedge-shaped 30 (Fig. 27), the vertex of the wedge lying in the center of the groove formed by the web of the type and the base of the wedge overlying the head of the rails. The upper portion of the opposing wedge-shaped ribs 291 35 are slightly bevelled towards each other so as to permit the entrance of the type at a time when they do not exactly align with the receiving channel. This provides in effect a type channel which is slightly larger 40 than is necessary to hold the type. However, it has been found that such a channel is limited due to the comparatively small size of the type to be cast, as it will be noticed that the grooves between the base portion and the head portion are comparatively 45 shallow, and therefore prevent the use of any considerable amount of loose play in the channels or the guiding members. Hence, it is desirable to provide some means which 50 may be associated with both the mold and the type channel guide block which will take care of a greater movement of the type than can be done by means of the guides 290 and the channels themselves.

55 In the embodiment illustrated, an intermediate guide member 295 (Figs. 25, 26 and 28), preferably made of a springy material, is mounted on the guide block 291. As illustrated in Fig. 6, this intermediate guide member comprises a body portion 296, which is retained in place on blocks of the guides 291 by means of a suitable screw 297 and has 60 arcuately extending arms 298 and 299, the outer extremities of which in their normal position, are adapted to overlie the ribs 291

of the guide blocks. The arms are comparatively thin relative to the width of the groove in the type. The uppermost portion of the extremities of the arms 298 and 299, as illustrated in Fig. 26, are wedge-shaped and adapted to embrace the type as shown in Fig. 25.

Referring now to the diagram of Fig. 28, it will be noted that the pitch circle 300 of the mold wheel slightly overlies the pitch circle 301 of the type receiving channels, and that the arms 298 and 299 of the intermediate guide blocks are substantially tangential with the pitch circle of the receiving channels, and the type 70 are substantially centrally located with reference to the pitch circle of the mold wheel. When a type reaches the position indicated by 302 in Fig. 28, the plunger 85 (which carries the upper wall of the mold), starts its downward action 55 to discharge the type, and as the type is discharged, it strikes on the bevelled nose 298' of the arm 298 of the intermediate type guide 295 and springs this arm outwardly, at the same time centering the type 70 with relation 90 to the intermediate member.

As the mold and receiving drums rotate, the type is carried to the position shown at 303 in Fig. 28, where the type is central relative to the intermediate guide member 295 of the guide 290. However, as the type continues in its movement to the position shown at 304, the type forces the arm 299 of the intermediate guide member to spring outwardly until the type has cleared the mold, at which time the arm 299 forces the type back towards a central position relative to the guide, where it is gripped between the arms 298 and 299.

On the succeeding revolution of the mold wheel, as a type is forced from the mold into the intermediate guideway, it follows the same steps as did the type 70. However, the type 70 will then be shoved downward by the newly discharged type and thus forced from the grip of the intermediate type guide into the guide 291. At all times one of the arms 298 or 299, of the intermediate guide are substantially in alignment with one of the ribs 291 of the guide 290, and at such time as the next succeeding type enters the bite of the intermediate guide member it will spring the arm 298 outwardly, and release its grip on the type 70 and permit the latter to pass into the guide block 291 and thence to the channels 287.

To retain the type in the receiving channels 287, there is provided at the base of each channel a retaining plate 310, pivotally mounted on the base plate 286, as by a screw 311. The retaining plate 310 is swung to one side or the other to permit the removal of type from the channel. When the channels in one of the drums 271 are filled with type, the receiving frame is swung in its bearings 130

and the other drum presented for coaction with the mold wheel. The receiving drums are driven by mechanism hereinafter to be described.

Reference has been made to there being the same number of channels in each of the receiving drums as there are molds on the mold wheel. This is on the theory that the machine is to be used with different matrices one for each channel, and it is desired to keep the product of each mold distinct. If however, all the type being cast by the machine have the same character, so that the product of any mold might be received in any channel, there would be no necessary relation between the number of channels in the receiving drum and the number of molds. In that case, by increasing the diameter of the receiving drum, the departure of its peripheral arc of travel from the arc of the mold wheel could be reduced and thus allow a larger period of time for transferring the type from the mold to the receiving drum. The same result can be accomplished where the molds are individually different, by making the receiving drum of a diameter which is a multiple of that of the mold wheel, but this tends to make the machine unduly bulky.

The driving mechanism for the casting machine comprises in general a motor 25 (Fig. 2), which is connected by suitable gearing to the main shaft 15 of the mold wheel. The shaft 15, by means of a suitable transmission, operates the melting pot pump and the receiving drums. As illustrated, the motor 25 is drivingly connected by means of a belt or chain 315 to a speed reduction unit 316, mounted on the frame member 12. A gear 317, drivingly mounted on a shaft 318 of the reduction unit drives a gear 319 mounted on one member of a clutch 320, the other member of which is rigid with the shaft 15. Hence, when the clutch is thrown into operation by means of a yoke 321, operated by a suitable operating lever (not shown), power will be applied to rotate the shaft 15 of the mold wheel.

The melting pot pump is driven by means of a pulley 225 (Figs. 2 and 18) rigidly secured to the pump shaft 224 and driven by a belt 226 and a pulley 227 drivingly mounted on the shaft 228 journalled in a bearing member 322. Drivingly mounted on the shaft 228 is a pulley 323, driven by a belt 324 which passes around the pulley 323 to a pulley 325, drivingly secured to the shaft 15, and thence back to a pulley 326, parallel with the pulley 323 and loosely mounted on the shaft 228, and from there to a pulley 327, loosely mounted on the shaft 15, and thence back to the pulley 323, thereby driving the melting pot pump from the shaft 15.

The type receiving mechanism is driven from a compound gear member 22 (Fig. 22), drivingly mounted on the shaft 15. The

compound gear member meshes with a gear wheel 340, mounted on a shaft 341 and journalled in bearings 342, mounted in the frame member 268. The gear 340 carries a plunger 343, which is adapted to coact with a recess 344 in the plate 280 of the receiving drum, which is in position to receive type from the mold wheel.

When it is desired to change from one receiving drum to the other an arm 345, rigidly secured to the shaft 341 withdraws the plunger 343. The arm 345 and shaft 341 are drawn downwardly by means of a lever (not shown), which has a suitable yoke 346 adapted to coact with a collar 347 rigidly secured to the shaft 341. The receiving frame is then swung manually about its pivot until the plate 280 of another drum is brought into position over the plunger 343 which then moves upwardly against the disc 280, until it enters the recess 344 in the disc thereby locking the gear 340 to the drum and thus rotating the drum at the same speed as the mold wheel.

An adjustment is provided whereby each drum may be aligned accurately relative to its respective disc 280 so that the channels of each drum will necessarily register with the molds as presented. This is best illustrated in Figs. 30 and 32. The recesses 344 in discs 280 comprise bushings 350, mounted in arcuately slotted openings 351. The bushings 350 are adjusted in the openings 351 by means of suitable adjusting screws 352 mounted in the discs 280.

The discharge of the type must be accomplished in a comparatively short interval of time. Therefore, the driving connection between the mold wheel and the type receiving drum must be very exact. In other words, there can be practically no lost motion or back lash in the drive. Therefore, the gear 22 is composed of two gear members (Figs. 22 and 31) mounted face to face, the teeth of one being a continuation of the teeth of the other. These two members are bolted together by means of suitable bolts 352 passing through slotted openings 353 in one of the gear members. In this manner, when wear is encountered between the compound gear 22 and driving gear 340 of the type receiving mechanism, the two gear members may be rotated slightly relative to each other, thereby increasing the width of the teeth of the compound gear member 22 and taking up the loss, due to wear on either of the gears. The compound gear members are then clamped together and operated as before.

What is claimed as new is:

1. In a machine for casting, the combination of a rotary wheel having about its periphery molds for both the article and the sprue, means for injecting molten material into such combined cavity, and means for

thereafter shearing off the sprue and still later ejecting the article from the wheel.

2. In a machine for casting short grooved type, the combination of a rotary wheel having about its periphery molds for both the type and the sprue, means for injecting molten metal into such combined cavity, means for thereafter shearing off the sprue, and means for ejecting the type from the wheel in a direction transverse to the length of the type.

3. In a machine of the character described, the combination of a rotary wheel carrying about its periphery a series of molds, a part of each mold being defined by a member slidably guided in the wheel to move in a direction transverse to the plane of rotation of the wheel, and means for moving said member transversely of the mold cavity.

4. In a casting machine, the combination with a nozzle and means for forcing molten metal through it, of a rotary wheel carrying a series of molds adapted to be brought successively into cooperation with the nozzle, each mold having one of its surfaces on a member carried by the wheel and slidably guided in a direction parallel with the wheel axis, means for moving said member from such direction to eject the casting.

5. In a machine of the character described, the combination of a rotary wheel having about its peripheral portion a series of molds, each mold having a cavity for the article to be cast and a cavity for the sprue, one wall of the sprue being defined by a movable member guided parallel with the axis of rotation of the wheel, and means for moving said member to shear off the sprue.

6. In a machine of the character described, the combination of a rotary wheel having about its periphery a series of cavities for defining the article to be cast and the sprue, a pair of bars for each cavity slidably mounted in the mold wheel in a direction parallel with the axis of rotation of the wheel, one of said bars having its end defining a wall of the article cast and the other having its end defining a wall of the sprue, and means for operating said bars successively to shear off the sprue and eject the article.

7. In a machine of the character described, the combination of communicating cavities for defining the article to be cast and the sprue, a pair of bars for each cavity slidably mounted, one of said bars having its end defining a wall of the article cast and the other having its end defining the wall of the sprue, and means for operating said bars successively to shear off the sprue and eject the article.

8. In a machine of the character described, the combination of a continuously moving rotary mold wheel, a series of molds about the periphery thereof, each mold having one of its walls carried by a bar radially mounted in

the wheel, means for withdrawing the bar inward radially as the wheel rotates to free the casting, and means for ejecting such casting while the wheel is rotating.

9. In a machine of the character described, the combination of a rotary mold wheel, a series of molds about the periphery thereof, each mold having one of its walls carried by a bar radially mounted in the wheel, means for withdrawing the bar inwardly radially as the wheel rotates, a member associated with the mold and providing the wall opposite the bar, and means for operating said member to eject the casting when the radial bar has been withdrawn sufficiently to free the casting.

10. In a machine of the character described, the combination of a rotary mold wheel, a series of molds about the periphery thereof, each mold having a sprue cavity with one of its walls carried by a bar radially mounted in the wheel, means for withdrawing the bar inward radially as the wheel rotates, a movable member associated with each mold and forming the opposite wall of the sprue from the radial bar mentioned, and means for operating said member to shear off the sprue when the radial bar is withdrawn sufficiently to free the sprue.

11. The combination of a mold wheel having a series of molds about its periphery, each mold having one surface thereof defined by a movable mold member carried by the wheel and having its opposite surface defined by two movable bars, and means operating as the wheel rotates to retract the movable member on the wheel part way to free the sprue and then operating one of said bars to shear off the sprue, and thereafter withdrawing the movable member still further to free the article cast and operating the other bar to eject such article.

12. The combination of a mold having a combined article and sprue cavity with one surface thereof defined by a movable member, and having its opposite surface defined by two movable bars, to retract the movable member part way to free the sprue, means to operate one of the bars in cooperation with the partly withdrawn member to shear off the sprue, means for withdrawing the movable member still further to free the article cast, and means for thereafter operating the other bar to eject such article.

13. In a casting machine, the combination of a rotary wheel, a series of molds carried adjacent the periphery thereof, a series of radially movable bars mounted in the wheel and forming one surface of the mold, and matrix blocks removably carried by said bars, and arranged to form another surface of said molds.

14. In a casting machine, the combination of a rotary wheel, a series of molds carried

on the peripheral portion thereof and having an article cavity and a communicating sprue cavity, a series of radially mounted bars carried in the wheel forming one surface of both cavities, matrix blocks carried by said bars, and means for automatically withdrawing the bars and matrix blocks inwardly first to free the sprue and thereafter to free the article cast.

15. In a casting machine, the combination of a rotary wheel, a series of members carried thereby and forming one wall of molds about the periphery of the wheel, a yielding support for such members onto which they come successively, and means for ejecting molten metal into the mold cavity at a time when the member is on the support.

16. In a casting machine, the combination of a movable carrier, a series of members carried thereby and forming one wall of sprue cavities arranged about the periphery of the wheel, a yielding support for such members onto which they come successively, and means for shearing off the sprue of the casting at a time when the member is on said support.

17. In a machine of the character described, the combination of a rotary mold wheel, a series of radial bars mounted therein and each constituting a wall of a mold cavity, a roller, and a spring pressing said roller toward the plane of rotation of the mold wheel so that the successive bars may engage the roller.

18. In a machine of the character described, the combination with a melting pot, pump and nozzle of a rotary mold wheel having in its peripheral portion a series of mold cavities, a series of radial bars mounted in the mold wheel constituting a wall of the mold cavity, a roller, a slidably guided block carrying the roller, and a spring pressing said block toward the plane of rotation of the mold wheel so that the successive bars may engage the roller.

45. 19. In a casting machine the combination of a horizontal rotatable wheel having downwardly facing radial grooves in its underside, molds carried by the wheel in the periphery thereof and each including a bottom bar 50 radially slidable in said radial grooves and forming the bottom wall of said mold, and means for holding the bars in place.

20. In a casting machine, the combination of a rotatable wheel having radial grooves, 55 molds carried by the wheel in the periphery thereof and each including a bar radially slidable in said radial grooves, and buttons secured to the mold wheel and each overhanging two adjacent radial bars, said buttons 60 being turnable to release such bars.

21. In a casting machine, the combination of a rotary mold wheel, a series of molds carried about the periphery thereof, a series of members slidably mounted in the mold 65 wheel in a direction parallel with the axis of

the wheel, each member having its lower end defining a part of the mold cavity, an oil guide at the top of the mold bar and means whereby the oil guide is automatically fed with oil as the wheel rotates.

22. In a machine of the character described, the combination of a rotary wheel having about its periphery a series of cavities for defining the article to be cast and the sprue, a pair of members side by side for each cavity slidably mounted in the mold wheel in a direction parallel with the axis of rotation of the wheel, one of said members having its end defining the wall of the sprue, means for operating said members successively to shear off the sprue and eject the article, an oil guide associated with the various molds and located respectively at the tops of the two members and adapted to direct oil to them, and a depending oil wick which such guides engage one after the other as the wheel rotates.

23. In a machine for casting short grooved type, the combination of a mold wheel having a series of molds about its periphery, each mold having the opposite sides of its cavity defined by three surfaces, the intermediate ones of which are nearer together than either of the extreme surfaces to provide a neck between the foot and head of the type, a withdrawable member forming one side surface of the type cavity and a plunger forming the other side surface, means for withdrawing the withdrawable member and means for operating the plunger to eject the type.

24. In a machine for casting Multigraph type, the combination of a mold wheel having about its periphery a series of cavities, each cavity having its side surface made up of the edges of three bars, the intermediate bars project nearer each other than the extreme bars, a movable bottom member for the type cavity, a matrix for the front of the cavity, and a plunger for the top of the cavity.

25. In a machine for casting Multigraph type, the combination of a mold wheel having a cavity with its side surface made up of the edges of three zones, the intermediate zones being nearer each other than the extreme zones, a bottom bar for the type cavity, a matrix block for the front of the cavity carried by the bottom bar, a plunger for the top of the cavity, mechanism for withdrawing the bottom bar and thereby this matrix block, and means for operating the plunger to eject the type when the bottom bar has been withdrawn.

26. In a machine for casting Multigraph type, the combination with a mold wheel having about its periphery a series of cavities each cavity having its side surface made up of three zones, the intermediate zones being nearer each other than the extreme zones, a bottom bar for the type cavity, a matrix for the front of the cavity carried by the bottom

bar, a plunger for the top of the cavity, each mold having a sprue cavity leading to the type cavity, the same bars which constitutes the bottom of the type cavity constituting also the bottom of the sprue cavity, and a plunger the lower end of which constitutes the top of the sprue cavity.

27. In a casting machine, the combination of a rotary wheel having molds about its periphery, a nozzle for ejecting material into the molds successively, a shield block embracing the nozzle and having a concave surface adjacent the mold wheel, and a support for the shield block carried independently of the nozzle and mold wheel.

28. In a casting machine, the combination of a rotary wheel having molds about its periphery, a nozzle for ejecting molten material into the molds successively, a shield block embracing the nozzle and having a concave surface adjacent the mold wheel, a thrust member against which the inner surface of the shield bears beyond the mold wheel, and means for adjusting said thrust member outwardly to compensate for heat distortion of the parts.

29. In a casting machine, the combination with a nozzle and means for discharging material through it, of a rotary mold wheel carrying a series of matrices, and means for yieldingly pressing any matrix which is in the casting position toward the nozzle.

30. In a casting machine, the combination of a nozzle, of a rotary mold wheel, a series of radially slidable bars therein, each carrying a matrix to cooperate with the nozzle, means for moving said bars outward radially, and yielding means for opposing inward movement of the bar when it is in casting position.

31. In a casting machine, the combination with a nozzle of a rotary wheel having a series of molds about its periphery, each mold including a matrix movable radially inward, a cam, the rotation of the wheel causing the successive matrices to be acted on by the cam to be thereby shoved outwardly, and a spring acting on said cam whereby the cam yieldingly holds the matrix in casting position.

32. In a casting machine, the combination with a nozzle for molten material, of a rotary wheel having a series of molds about its periphery, each mold including a matrix movable radially inward, a cam coacting with the successive matrices to shove them outwardly, said cam being pivotally mounted, but approximately stationary in operation, and a spring acting on said cam and tending to swing it outwardly whereby the cam yieldingly holds the matrix in casting position.

33. In a casting machine, the combination with a mold wheel having a series of molds about its periphery, each mold having a wall defined by a bar radially movable in the wheel, a matrix in a block forming another

face of the mold, said block being mounted in a recess in the bar, the bar and matrix block being removably mounted in a groove in the wheel.

34. In a casting machine, the combination of a rotary wheel having a series of molds in its periphery, a member mounted on the mold wheel and carrying a part of the mold cavity, a stationary cam, and means carried by the member and engaging the cam whereby the member may be moved crosswise of the mold cavity following the casting operation.

35. In a casting machine, the combination of a rotary wheel having a series of molds in its periphery, a member slidably mounted parallel with the axis of the mold wheel and carrying a part of the mold cavity, a stationary cam, and a roller carried by the member and engaging the cam, whereby the member may be moved crosswise of the mold cavity following the casting operation.

36. In a casting machine, the combination of a rotary wheel having a series of molds in its periphery each having a sprue cavity, a member slidably mounted parallel with the axis of the mold wheel and carrying a part of the wall of the cavity, a stationary cam, and a roller carried by the member and engaging the cam whereby the member may be moved crosswise of the mold cavity following the casting operation to shear off the sprue cast in the cavity.

37. In a casting machine, the combination of a movable mold, a pair of bars slidably mounted side by side parallel with the axis of the wheel, one bar carrying a surface of the cavity for the article proper and the other a surface of the cavity for the sprue, a pair of stationary grooved cams facing each other, a roller on one bar occupying one cam groove, and a roller on the other bar occupying the other cam groove.

38. In a casting machine, the combination of means carrying a mold cavity and a communicating sprue cavity, a pair of bars the ends of which define a wall of the mold cavity and sprue cavity respectively, a pair of operating bars aligning with the cavity bars and interlocked with them, means for guiding the cavity bars and operating bars, and mechanism engaging the operating bars to move the cavity bars.

39. In a casting machine, the combination of a rotary wheel having a series of molds about its periphery, a series of bars defining a wall of the mold, means for pushing said bars outwardly and yieldingly holding them during the casting operation, and means for positively drawing them inwardly following said operation.

40. In a casting machine, the combination of a rotary wheel, having a series of molds about its periphery, a series of bars each defining a wall of the mold, means for pushing said bars outwardly and yieldingly holding

them during the casting operation, means for positively drawing them inwardly in two steps following said operation, a pair of slideable plungers defining the main and sprue cavities opposite the said radial bars, and means for operating said plungers successively following the casting operation.

41. In a casting machine, the combination with a nozzle adapted to inject molten material, of a horizontal rotary wheel having a series of molds about its periphery, a vertical shaft for said wheel, a bearing for said shaft adjacent the wheel, said shaft being suspended by said bearing, and a bearing 10 for the lower end of the shaft slidably mounted parallel with the shaft axis.

42. In a casting machine, the combination of a vertical shaft, a bearing engaging the same near its upper end and suspending 20 the shaft, a vertically slideable bearing for the shaft near its lower end, a rotary member on said shaft having means for carrying type at its periphery, a series of longitudinal type channels carried by said member, a rotary mold wheel, and means for discharging type from the mold wheel into said member.

43. In a casting machine, the combination of a vertical shaft, a bearing engaging the 30 same near its upper end and suspending the shaft, a vertically slideable bearing for the shaft near its lower end, a rotary member on said shaft having means for carrying type at its periphery.

44. In a casting machine, the combination of a mold carrier, a melting pot associated therewith, and a continuously moving rotary casting-receiving mechanism wherein the path of the type in the mold carrier is 40 substantially tangent to the path of the type in the receiving mechanism.

45. In a casting machine, the combination of a rotary mold carrier, a rotary casting receiving mechanism, and means to drive the receiving mechanism in synchronism with the carrier.

46. In a casting machine, the combination of a rotary mold carrier, a rotary receiving mechanism wherein the path of the type in the mold carrier is substantially tangential to the path of the type in the receiving mechanism, and means for transferring type from a carrier to the receiver while both are moving.

47. In a casting machine, a continuously moving rotary mold carrier, a relatively stationary melting pot associated therewith a rotary casting receiving mechanism, wherein in the outer peripheries of said mold member and said receiving mechanism are substantially intersecting circles one circle being disposed above the other, means associated with the mold carrier to drive the receiving mechanism in synchronism with the carrier, and means for transferring castings 60

from the mold carrier to the receiving mechanism while they are both rotating.

48. The combination of a rotary mold carrier having a series of molds about its periphery, each mold having an ejector associated with it, a rotary receiver having a series of individual channels each arranged to receive type directly from the mold carrier and store a plurality of individual type, means for rotating the mold carrier and receiver simultaneously, and means for operating the ejector to cause a discharge of the casting from the mold carrier to the receiver while both are moving.

49. The combination of a horizontal continuously rotary wheel having molds about its periphery, a rotary receiving mechanism having molds about its periphery, a rotary receiving mechanism having a series of upright channels, said receiving mechanism underhanging the mold wheel, downwardly acting plungers carried by the mold wheel, one for each mold, means for rotating said wheel and receiving mechanism simultaneously and at the same peripheral speed, and means for operating the plungers successively to shove castings downwardly from the mold wheel into the receiver.

50. In a casting machine, the combination of a mold carrier, a melting pot associated therewith, a plurality of interchangeable casting receiving units arranged to receive individual castings, wherein one receiving unit may cooperate with the mold carrier while the remaining units are in position to be emptied.

51. In a casting machine, a rotatory mold carrier, and a plurality of casting receiving mechanisms adapted to be interchangeably associated with the mold carrier.

52. In a casting machine, the combination of a rotary mold carrier, a melting pot associated therewith, a plurality of interchangeable casting receiving units, each rotatably mounted and bodily shiftable whereby one receiving unit may cooperate with the mold carrier while the remaining units are in position to be emptied.

53. In a casting machine, the combination of a mold carrier, a melting pot associated therewith, a plurality of casting receiving mechanisms, each rotatably mounted as a unit and all of the units rotatable as a whole, whereby one receiving unit may rotatably cooperate with the mold carrier while the remaining units are comparatively stationary, and one of them being in position to be emptied.

54. In a casting machine, the combination of a rotary mold carrier, a melting pot associated therewith, of a pair of rotatably mounted casting receiving units, wherein one of said receiving units may rotate in cooperation with the mold carrier and at the same periph-

eral speed, while the other unit is in a relatively stationary position to be emptied.

55. In a casting machine, a rotary mold carrier, having a plurality of molds, and a plurality of rotatable receiving mechanisms for the castings, each of said receiving mechanisms arranged to keep the product of each individual mold separate from the products of the other molds.

10 56. In a casting machine, a rotary mold carrier having a plurality of molds, each mold comprising a casting cavity and a sprue cavity, means associated with each sprue cavity to discharge the casting therefrom.

15 57. In a casting machine, a rotary mold carrier having a plurality of molds, each mold including a casting cavity and a sprue cavity, means associated with each sprue cavity to shear the sprue from the casting, means 20 for discharging the sprue, means associated with each mold for discharging the casting therefrom, and rotary means adapted to receive the castings as they are discharged from said molds.

25 58. In a casting machine, a rotary mold carrier having a plurality of molds, each mold including a casting cavity and a sprue cavity, a melting pot associated with said molds, individual means associated with each 30 sprue cavity to shear the sprue from the casting, individual means for discharging the sprue, individual means associated with each mold for discharging the casting therefrom, individual receiving means adapted to 35 receive the castings from each individual mold, and a guideway associated with each receiving means adapted to guide the castings from the mold to the receiving means.

59. The combination of a rotary mold 40 wheel having molds about its periphery, means for ejecting molten material thereinto, a rotary receiving member adapted to stand with a portion adjacent to a portion of the wheel, means for forcing castings from the 45 wheel to the receiving member, and means for varying the entrance to the receiving member to increase the period of time available for discharging as the two wheels are rotated.

50 60. The combination of a rotary wheel having a series of molds about its periphery, a rotary receiving member having a series of channels, means for driving the mold wheel and receiving member in unison so that 55 each mold becomes associated with a receiving channel, means for ejecting a casting from the mold to the receiving channel, and movable means associated with the entrance to each receiving channel to enable substantial 60 registration between such channel and mold cavity for a materially longer period of time than their actual coincidence.

61. The combination of a rotary wheel having a series of molds about its periphery, 65 a rotary receiving member having a series of

individual receptacles, means for driving the mold wheel and receiving member so that each mold becomes associated with a particular receptacle, means for ejecting the casting from the mold, and a pair of spring jaws at the entrance to each receptacle to enable substantial registration between such receptacle and mold for a considerable distance of travel.

62. In a machine of the character described, the combination of a movable group of molds, a rotary receiving member having individual receptacles, gearing connected with the group of molds for simultaneous movement, and a movable lock adapted to connect said gearing with the receiving member or disconnect it therefrom.

63. The combination of a rotary wheel having a series of molds about its periphery, a rotary receiving member, a gear driven with the mold, a gear meshing therewith and coaxial with the receiving member and a bolt on the last mentioned gear adapted to coact with the receiving member to lock the gear thereto.

64. The combination of a movable group of molds, a rotary receiving member, a coaxially mounted driving device therefor, and means adapted to interlock the driving device and the receiving mechanism, there being an adjustment in such interlocking device to enable an angular change of the receiver with reference to its driver.

65. In a machine of the character described, the combination of a movable group of molds, a plurality of interchangeable rotary receiving members having individual receptacles, a driving device connected with the group of molds for simultaneous movement, and a lock adapted to connect said driving device with that receiving member which is in the active position to receive articles from the molds.

66. In a machine of the character described, the combination of a rotary mold wheel having molds about its periphery, a rotatable frame on an axis parallel with the mold wheel, two rotatable drums of equal size carried by said frame diametrically opposite each other, each drum having longitudinal type-receiving channels adapted to coact with the molds, whereby one drum may be in the act of being filled while the other is idle for removal.

67. The combination of a rotary mold wheel having a series of molds adjacent its periphery, a rotatable frame on an axis parallel with the wheel, a plurality of receiving drums mounted in the frame each on an axis parallel with the frame axis, each drum having a series of upright channels, means whereby either drum may be positioned as desired in cooperation with the mold wheel, means whereby when the drum is so positioned it may be driven at the same periph-

eral speed as the mold wheel, means for discharging type from successive molds of the mold wheel to successive channels of the active drum, and means for opening the channels of the inactive drum to enable discharge of type therefrom.

In testimony whereof, I hereunto affix my signature.

AGNES M. DEMMING,

10 *Administratrix of the Estate of William J. Demming, Deceased.*
